(57) **CLAIM**

The ornamental design for a sofa bed, as shown and described.

DESCRIPTION

FIG. 1 is a front view of the sofa bed in a first position; FIG. 2 is a right view of the sofa bed in the first position; FIG. 3 is a back view of the sofa bed in the first position; FIG. 4 is a front, right side, perspective view of the sofa bed in the first position; FIG. 5 is a front, right side, perspective view of the sofa bed in a second position; FIG. 6 is a front, right side, perspective view of the sofa bed in a third position; FIG. 7 is a front, left side, perspective view of the sofa bed in a fourth position; and, FIG. 8 is a front, left side, perspective view of the sofa bed in a fifth position. The broken line showing of internal frame structure is for the purpose of illustrating portions of the sofa bed and forms no part of the claimed design.

1 Claim, 8 Drawing Sheets(56)
